(57) **CLAIM**

The ornamental design for an impact sprinkler as shown and described.

DESCRIPTION

FIG. 1 is a first top perspective view of an impact sprinkler, according to our new design;

FIG. 2 is a second top perspective view of the impact sprinkler;

FIG. 3 is a first bottom perspective view of the impact sprinkler;

FIG. 4 is a second bottom perspective view of the impact sprinkler;

FIG. 5 is a front elevational view of the impact sprinkler;

FIG. 6 is a rear elevational view of the impact sprinkler;

FIG. 7 is a top plan view of the impact sprinkler;

FIG. 8 is a bottom plan view of the impact sprinkler;

FIG. 9 is a left side elevational view of the impact sprinkler;

FIG. 10 is a right side elevational view of the impact sprinkler; and,

FIG. 11 is a left side elevational view of the impact sprinkler in an alternate position.

The dash-dash broken lines in the figures are included for the purpose of depicting portions of the impact sprinkler that form no part of the claimed design. The dot-dash broken lines in the figures define boundaries of the claimed design and form no part of the claimed design. The portion of the impact sprinkler obscured by the unclaimed knob that is not visible in any of the provided views is unclaimed and, therefore, forms no portion of the claimed design.

1 Claim, 11 Drawing Sheets
